HAIR NET

Donald R. McCown, San Diego, Calif.

Application September 25, 1935, Serial No. 42,011

7 Claims. (Cl. 132—49)

My invention relates to hair nets, more particularly to hair nets adapted to be worn when one is sleeping or merely reclining, and the objects of my invention are:

5 First, to provide a hair net of this class which may be secured in position on the head and will not readily be dislodged or removed accidentally;

Second, to provide a hair net of this class which covers the entire head of hair when the hair is 10 arranged in its normal manner so that all portions of the head of hair are retained in their proper position as long as the hair net is worn;

Third, to provide a hair net of this class which though covering the entire head of hair permits 15 circulation of air around and through the hair so that the hair may readily dry, thus providing a hair net of this class which is particularly adapted for use in setting the hair after finger waves or other method of training the hair have been used;

20 Fourth, to provide a hair net of this class which is adapted to stretch slightly at various portions and thus conform substantially to the irregularities of the hair on the head;

Fifth, to provide a hair net of this class which is particularly simple and economical of construction and manufacture, there being but few parts and these parts being easily formed;

Sixth, to provide a novel means of securing the 30 hair net on the head and reinforcing the net at the same time; and

Seventh, to provide a hair net of this class which is novel of construction, durable, efficient in its action, and which will not readily deteriorate or get out of order.

35 With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

40 Figure 1 is a front perspective view of my hair net as it appears when worn; Fig. 2 is a rear perspective view of my hair net when worn; Fig. 3 is a side elevational view of my hair net as it appears when worn; Fig. 4 is a rear perspective view of my hair net when ready to be positioned 45 on the head of the wearer and showing the tape 4 and showing the fold as used in forming the side members 2 and 3; Fig. 5 is a reduced developed view of the top section 1; Fig. 6 is a reduced developed view of one of the side 50 members; Fig. 7 a reduced developed view of one of the side members 2 or 3 in folded form showing the contraction of the same at the back when formed ready for use in the net; Fig. 8 is a diagrammatic view showing the fold of the material 55 in the side members 2 and 3 along the line 8—8 of Fig. 4, and Fig. 9 is a diagrammatic view showing the seam construction of the seams 4.

Similar characters of reference refer to similar parts and portions throughout the several 10 views of the drawings.

The top section 1, side sections 2 and 3, section connection seams 4, back reinforcing seam 5, and binding tape and tie string 6, constitute the principal parts and portions of my hair net.

The top section 1 shaped substantially as shown in Fig. 5 of the drawings being slightly wider at its central portion than at its ends and its front end being considerably wider than its rear end, the rear end practically coming to a point, 20 as shown best in Fig. 5 of the drawings, and providing long curved side edges 1a and 1b, front edge 1c and rear edge 1d. There are also provided two side sections 2 and 3 which are similarly shaped, as shown best in Fig. 6 of the drawings, each having one substantially straight side 2a, curved side 2b, back straight side 2c, and beveled cut 2d. In forming the side sections 2 and 3 the straight portion 2c is folded upon itself, as shown in Figs. 4 and 7 of the drawings, 30 thus narrowing the rear portions of the sections 2 and 3 and at the same time reinforcing said sections at the rear portion. These sections 1, 2 and 3 are formed of netting or suitable gauze material which permits complete access of air to 35 the hair, the hair net being practically foraminous throughout.

The curved portions 1a and 1b of the section 1 are joined to the curved portions 2b of the sections 2 and 3 by means of the seams 4, and the 40 back edge including the folds is provided with a reinforcing seam 5, as shown best in Figs. 2 and 4 of the drawings.

Then secured over the portion 1c of the section 1 and the portions 2a of the sections 2 and 3 is a light binding tape member 6 which is folded over the edges of these members and sewed thereto forming a reinforcement along the edge, and the folded ends of this binding tape 6 are 45 extended some distance past the ends of the seam 5 and form the strings which are crossed at the back and drawn tight so as to draw the seam 5 across itself, as shown best in Figs. 2 and 3 of the drawings, and the two ends are tied together 50 55

over the front portion by means of a knot 6a, shown best in Fig. 1 of the drawings.

Thus it will be noted that the back portion is folded in overlapped relation at the back when 5 in position on the head as well as the folds in the sections 2 and 3 for narrowing the side sections at the back; thus providing a form fitting net for the head adapted for various sizes and shaped 10 heads and reinforced and secured in position so that it is substantially immovable on the head by means of the reinforcing tape 6 with extended string portions.

It is obvious that once the hair net is positioned and the ends of the string secured by means of a 15 knot 6a over the front portion of the head back of the front portion of the net, that it is practically impossible for the hair net to shift so as to dislodge the arrangement of the hair or to work off of the head; thus the hair net is particularly adapted for use when one is lying down whereby one may retain the hair in desired prepared arrangement when lying down.

Though I have shown and described a particular construction, combination and arrangement 25 of parts and portions, I do not wish to be limited to this particular construction, combination and arrangement but desire to include in the scope of my invention the construction, combination and arrangement substantially as set forth in the 30 appended claims.

Having thus described my invention, what I claim as new and desire to secure by Letters Patent is:

1. In a hair net, a plurality of section members 35 formed of foraminous cloth of sufficient body to permit stitching, said section members sewed together along portions of their margins to form a substantially semi-spherical head covering, one side of said structure being open upwardly some 40 distance from the lower margin to form the middle back side of said net, and the sides of said open portion being adapted to fold into overlapped relation at the back, and some of said sections being formed in folded secured reinforcing relation from 45 said opening forwardly to provide an adjustable head fitting foraminous structure.

2. In a hair net, a plurality of section members 50 formed of foraminous cloth of sufficient body to permit stitching, said section members sewed together along portions of their margins to form a substantially semi-spherical head covering, one side of said structure being open upwardly some 55 distance from the lower margin to form the middle back side of said net, and the sides of said open portion being adapted to fold into overlapped relation at the back, some of said sections being formed in folded secured reinforcing relation from 60 said opening forwardly to provide an adjustable head fitting foraminous structure, and a reinforcing tape secured around the edge of said head covering and having its ends extended some distance providing long slender string members at the back adapted to cross at the back and adapted to be brought over the front portion of the head and tied.

3. In a hair net, a plurality of section members 5 formed of foraminous cloth of sufficient body to permit stitching and shaped substantially in semi-spherical form, said section members being stitched along portions of their margins and a portion of said section members provided with folded relatively secured reinforcing portions at one side, said folded reinforcing sections terminating in an open portion extending into the main portion providing reinforced overlapped portions 10 and forming the central rear portion of the neck.

4. In a hair net, a plurality of section members 15 formed of foraminous cloth of sufficient body to permit stitching and shaped substantially in semi-spherical form, said section members being 20 stitched along portions of their margins and a portion of said section members provided with folded relatively secured reinforcing portions at one side, said folded reinforcing sections terminating in an open portion extending into the main 25 portion providing reinforced overlapped portions and forming the central rear portion of the neck, and long slender extended tie strings secured to the margin of said structure and in engagement with said folded reinforced portion. 30

5. In a hair net, a plurality of section members, 35 formed of foraminous cloth of sufficient body to permit stitching, said section members sewed together along portions of their margins, the normally back side of said structure at the middle 40 being open from its lower side upwardly some distance adapted to fold into overlapped relation adapted to form a head fitting foraminous structure.

6. In a hair net, a plurality of section members 45 formed of foraminous cloth of sufficient body to permit stitching, said section members sewed together along portions of their margins so as to form a substantially semi-spherical foraminous structure, but provided with an extended open 50 portion in one side forming the back side of the net, and a portion of the edge of the structure at the opening being reinforced with folded irregular portions of similar foraminous cloth. 55

7. In a hair net, a plurality of section members 60 formed of foraminous cloth of sufficient body to permit stitching, said section members sewed together along portions of their margins so as to form a substantially semi-spherical foraminous structure but provided with an extended open portion in one side forming the back side of the net, a portion of the edge of the structure at the opening being reinforced with folded irregular portions of similar foraminous cloth, and a reinforcing tape secured to the margin of said structure except the open portion and having its ends extended at the open portion some distance providing long slender string members at the back adapted to cross at the back and to be brought over the front portion of the head overlapping the reinforced sides at the open portion and forming a head fitting foraminous structure. 65

DONALD R. McCOWN.
